UNITED STATES PATENT OFFICE.

ANDREW LOKEN, OF HARVEY, NORTH DAKOTA.

ROTARY AIR-COMPRESSOR.

1,321,764.

Specification of Letters Patent. Patented Nov. 11, 1919.

Application filed January 15, 1919. Serial No. 271,241.

To all whom it may concern:

Be it known that I, ANDREW LOKEN, a citizen of Norway, residing at Harvey, in the county of Wells and State of North Dakota, have invented new and useful Improvements in Rotary Air-Compressors, of which the following is a specification.

This invention relates to a rotary air compressor the object in view being to produce a high speed powerful and practical rotary air compressor involving a number of cylinders which are mounted upon and carried by a rotary support, the latter being driven by an engine or motor of any kind and the air compressed by all of the cylinders being directed to a common receiving manifold and conducted therefrom to a storage tank or reservoir.

One of the main features of the invention resides in the particular means for actuating the reciprocating pistons of the air compressing cylinders which are carried by said rotary support, said piston actuating means being of a simple character, involving a minimum number of working parts and adding thereby to the life and durability of the air compressor as a whole.

With the above and other objects in view, the invention consists in the novel construction, combination and arrangement herein fully described, illustrated and claimed.

In the accompanying drawings:—

Figure 1 is a front elevation of the rotary air compressor, certain parts being broken away in section, for better illustration.

Fig. 2 is a vertical transverse section through the same taken adjacent to the rotary shaft of the compressor.

The rotary air compressor contemplated in this invention comprises a suitable supporting base A which is shown as embodying two substantially A shaped members having bearings 1 at the top thereof in which is journaled the rotary compressor as illustrated in Figs. 1 and 2 of the drawings. Mounted in fixed relation to and surrounding the shaft 2 is a rotary support 3 embodying a rim as shown. Carried by said rotary support is a circular series of air compressing cylinders 4 arranged equal distances from the center of said shaft 2. The cylinders 4 are supported at their inner ends by means of a spider 5 which may be common to all of the cylinders as shown in Fig. 1. Each cylinder is supported at its outer end by means of a U-shaped bracket 6 the ex-

tremities of the arms of which are bent outwardly to form seats 7, the latter being secured to the rotary support 3 by fastening means 8.

Mounted for reciprocatory motion in each of the cylinders 4 is a piston 9 having a rod 10 which extends through a stuffing box 11 in the outer cylinder head and has fixedly secured or related thereto a slotted cross head 12, the slot in the cross head extending transversely or at a right angle to the longitudinal axis of the rod 10. The actuating means for each piston consists of a short crank shaft 13 having a crank 14 provided with a crank pin 15 which works in the respective slotted cross head 12, the pins at 15 being preferably surrounded by an anti-friction roller 16 for an obvious purpose. Each piston actuating crank is balanced by means of a pendulous weight 17 which always hangs in a certain position and prevents the crank shaft 13 from rotating. Each crank shaft 13 is journaled in a supporting bracket 18 which is substantially V-shaped and secured to the rotary member 3 by means of fastening means 19.

Each of the air compressing cylinders 4 is provided in both heads or ends thereof with an automatic inlet valve 20 and is also provided in the opposite ends thereof with air outlet check valves 21 which communicate with a manifold pipe 22 from which a manifold connection 23 extends inwardly to the rotary shaft 2. The compressed air from all of the manifold connections 23 is delivered to a non-rotary receiving manifold 24 through a longitudinal passage or bore 25 in the shaft 2 as shown in Fig. 2. The shaft 2 rotates within the receiving manifold 24 and the latter is provided with holes 26 which intersect the passage 25 and deliver the air therefrom to the receiving manifold 24. From the manifold 24, the compressed air is delivered through a discharge pipe 27 to a compressed air storage tank or reservoir.

By means of the construction and arrangement described it will be seen that I have produced a high speed rotary air compressor in which any desired number of air compressor cylinders may be mounted upon a common rotary support which together with the cylinders and other connections hereinabove described constitutes a fly wheel. This enables the rotary air compressor to be driven economically by a comparatively

small motor. The number of air compressing cylinders may be increased or diminished according to the capacity of the air compressor.

5. I do not desire to be restricted to the exact arrangement shown and described it being obvious that the rotary air compressor is susceptible of many changes in the form, proportion and minor details of construction, which may accordingly be resorted to without departing from the principle or sacrificing any of the advantages of the invention.

Having described the invention what I claim is:—

15. 1. A rotary air compressor, comprising a base, a rotary support, a rotary shaft journaled upon said base and having said rotary support fast thereon, a plurality of air compressing cylinders carried by said rotary support with their longitudinal axes radial to said shaft, reciprocatory pistons in said cylinders, rods attached to said pistons and extending radially outward therefrom, slotted cross-heads on said piston rods, balanced piston-actuating cranks having a journaled mounting upon and carried by said rotary support and having crank pins working in said slotted cross-heads, and a compressed air discharge pipe in communication with all of said cylinders.

20. 2. A rotary air compressor, comprising a base, a rotary support, a rotary shaft journaled upon said base and having said rotary support fast thereon, a plurality of air compressing cylinders carried by said rotary support with their longitudinal axes radial to said shaft, reciprocatory pistons in said cylinders, rods attached to said pistons and extending radially outward therefrom, slotted cross-heads on said piston rods, balanced piston-actuating cranks having a journaled mounting upon and carried by said rotary support and having crank pins working in said slotted cross-heads, and a compressed air discharge pipe in communication with all of said cylinders.

25. 3. A rotary air compressor, comprising a base, a rotary support, a rotary shaft journaled upon said base and having said rotary support fast thereon, a plurality of air compressing cylinders carried by said rotary support with their longitudinal axes radial to said shaft, reciprocatory pistons in said cylinders, rods attached to said pistons and extending radially outward therefrom, slotted cross-heads on said piston rods, balanced piston-actuating cranks having a journaled mounting upon and carried by said rotary support and having crank pins working in said slotted cross-heads, and a compressed air discharge pipe in communication with the shaft and the air compressing cylinders.

30. 3. A rotary air compressor, comprising a base, a rotary support, a rotary shaft journaled upon said base and having said rotary support fast thereon, a plurality of air compressing cylinders carried by said rotary support with their longitudinal axes radial to said shaft, reciprocatory pistons in said cylinders, rods attached to said pistons and extending radially outward therefrom, slotted cross-heads on said piston rods, balanced piston-actuating cranks having a journaled mounting upon and carried by said rotary support and having crank pins working in said slotted cross-heads, and a compressed air discharge pipe in communication with all of said cylinders, said pipe being non-rotary and said shaft being rotatable in said pipe.

35. 4. A rotary air compressor, comprising a base, a rotary support, a rotary shaft journaled upon said base and having said rotary support fast thereon, a plurality of air compressing cylinders carried by said rotary support with their longitudinal axes radial to said shaft, reciprocatory pistons in said cylinders, rods attached to said pistons and extending radially outward therefrom, slotted cross-heads on said piston rods, balanced piston-actuating cranks having a journaled mounting upon and carried by said rotary support and having crank pins working in said slotted cross-heads, and a compressed air discharge pipe in communication with all of said cylinders, each of said cranks being balanced and prevented from rotating by a pendulous weight fast thereon.

In testimony whereof I affix my signature.

ANDREW LOKEN.
